HAIR WAVING APPARATUS

David Re David, New York, N. Y.

Application August 25, 1931. Serial No. 559,336

1 Claim. (Cl. 219—24)

This invention relates to improvements in permanent waving apparatus and more particularly to an improved heating appliance for use in imparting a permanent or lasting wave to the human hair.

An object of this invention is the provision of an improved heating appliance for use in permanent waving, which is simple in construction and operation and durable in use. A further object is the provision of a device of the above character in which the free ends of the hair which have already been waved may be suitably held as to aid in the setting of the wave therein when the device is moved to wave the hair closer to the scalp. A further object is to provide a device of the above character which substantially eliminates the possibility of burning or overheating the hair already waved as the device is moved towards the scalp to treat unwaved portions of the hair.

Other objects will be in part obvious from the annexed drawing and in part hereinafter indicated in connection therewith by the following analysis of this invention.

This invention accordingly consists in the features of construction, combination of parts and in the unique relation of the members and in the relative proportioning and disposition thereof, all as more completely outlined herein.

To enable others skilled in the art to fully comprehend the underlying features thereof that they may embody the same by the numerous modifications in structure and relation contemplated by this invention, a drawing depicting a preferred form of the invention has been annexed as part of this disclosure, and in such drawing like characters of reference denote corresponding parts throughout all the views, in which

Fig. 1 is a side elevation of my improved hair waving device illustrating the disposition of the heating device to hair being waved as well as the holding or strands of hair which has already been waved;

Fig. 2 is an elevation of the device as shown in Fig. 1, looking in a direction sidewardly thereof;

Fig. 3 is an end view shown in Figs. 1 and 2;

Fig. 4 is a sectional detail of certain parts of my device;

Fig. 5 is a detail of one of the protective means associated with my device.

As is generally known, according to one method of imparting a permanent wave to the human hair, adjacent strands of the hair at their free ends are coiled or wrapped about a core and

thereafter enclosed within a heating member. The heat acts upon the hair to impart a set or wave thereto. When the free ends of such strands have been treated, the heating appliance is opened, permitting the coiled strands to be unwound from the core, and unwaved portions of the same strands, but closer to the scalp, are successively treated until the strands have been suitably waved throughout their lengths.

In the drawing, the reference character 5 designates a core upon which strands of hair are wrapped. The heating means to be associated about the strands wrapped on the core 5 include generally two hollow and substantially semi-anular sheaths 10 and 11, in each of which is mounted an electrical heating unit 12 usually consisting of the resistance wire wound or arranged on a mica sheet. Arcuate end blocks 13 are disposed at the ends of the hollow sheaths 10 and 11 and provide a closure therefor.

From each of the sheaths 10 and 11 extend operating arms generally designated at 15, each comprising a plate 16 having one end curved to conform with the curvature of the outer wall of the sheaths 10 and 11 and secured thereto as at 17. Insulating blocks 18 are associated with the plates 16 whereby to protect the hands of the operator from the heat engendered by the heating units 12.

Each of the plates 16 carry brackets 20 through which is threaded a fulcrum pin 21, on which the operating handles or grips 15 and sheets 10, 11 are movably pivoted. In order to urge the sheaths 10 and 11 into engagement, there is provided a spring 23 extending between the operating arms 15, the ends of which are seated in recesses 24, 25 formed respectively in insulating blocks 18 and associated plates 16. It will be seen that the spring 23 urges the operating arms 15 away from each other whereby the sheaths 10 and 11 are moved into enclosing relation about the fulcrum pin 21. When the operating handles 15 are gripped and urged towards each other, the sheaths, 10, 11 are moved into a separating relation.

Lead wires 27 from a suitable source of electrical energy extend into a recess 30 formed in each of the insulating blocks (Fig. 4) and are electrically connected to contact members 31 similarly mounted in blocks 18 and extending thru their bottom face. The said contact members 31, when the operating arms are fixed on the sheets 10, 11, engage with conducting screws 32 which are in turn electrically connected with the heating units 12. Preferably the said heat-

ing units 12 are connected in series whereby actuation of an operating switch (not shown) thereupon causes the heating units 12 to generate heat whereby the strands of hair enclosed by sheaths 10, 11 and coiled on the core 5 are heated.

By reference to Fig. 1, strands of hair are coiled on the core 5 and are thereafter wrapped with a pad 35 or the like, and enclosed within 10 the sheaths 10, 11. As the appliance is successively moved throughout the length of the strands of hair being treated and in a direction towards the scalp, it will be seen that hair already waved protrudes from the relatively rear end of the 15 heating sheaths 10 and 11. In order to provide a support for this already waved hair and generally designated at A, I mount from one of the operating arms 15 a relatively rearwardly extending rod 36 which terminates at its end portion in a right-angled arm 37. The portions of 20 the strands already waved and normally protruding from the heating sheaths 10, 11 are coiled on the rod 36, 37 in the manner illustrated. Such coiling of the hair aids in setting of the wave 25 imparted thereto within the sheaths 10 and 11 and further has a natural tendency of making the hair wavy.

I further provide semi-circular closure plates 30 40, 41 each associated with the relatively rear ends of the sheaths 10, 11 and provided with a central depression 42. The said plates 40, 41 are preferably of heat insulating material, and when brought into engagement, form a substantial 35 closure for the rear ends of the sheaths 10, 11 thus to protect the already waved portions A, of the hair strands from overheating.

At the relatively forward ends of the sheaths 10, 11 which may be positioned adjacent the scalp of the person whose hair is being treated, I provide heat insulating plugs 45 which may engage the scalp and which provide a space between the scalp and heating sheaths 10, 11. Thus, the possibility of the heated sheaths 11 engaging the head of the person being treated is eliminated.

Without further analysis the foregoing will so fully reveal the gist of this invention that others can by applying current knowledge readily adapt it for various applications without omitting certain features that, from the standpoint of the prior art, fairly constitute essential characteristics of the generic or specific aspects of this invention, and therefore such adaptations should and are intended to be comprehended with the meaning and range of equivalency of the following claim.

I claim:

Hair waving apparatus including hollow substantially semi-annular elements each enclosing an electrical heating unit, an operating arm extending from each of said elements, a flexible connection between said arms, means extending between said arms and operative to urge said elements into engagement, a core extending between said element and on which strands of hair are wrapped, and means extending from one of said arms in substantially parallel relation with the core on which the free ends of the strands wrapped on the core may be coiled.

DAVID RE DAVID.
